UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

STOPPING MECHANISM FOR LOOMS.

Application filed July 12, 1927. Serial No. 205,065.

This invention relates to looms and more particularly to means for stopping the loom on the occurrence of a warp or a weft fault.

It is now the common practice to equip looms with means for stopping the loom when a warp thread breaks or becomes too slack for weaving purposes, and also to stop the loom when the weft or filling fails to be laid in the shed. Such mechanisms, however, have introduced complications in loom structure, and one of the objects of the present invention is to provide means of simple and few parts for stopping the loom on the occurrence of either a warp or a weft fault.

On the occurrence of a warp fault it is desirable that the loom be stopped with the lay and shedding mechanism in proper positions for piecing up, and that such stopping of the loom shall be effected on the occurrence of a first fault in the warp. Should a fault occur in the weft, however, it is frequently preferable to continue the loom operation for a few picks, because the weft fault may be cured by the operation of the loom. This is particularly observable where the loom is of the filling replenishing type and where breakage of the weft may take place during the transfer of the filling carrier to the shuttle. In such cases the cause of the weft breakage may be due to some temporary condition at the replenishing side of the loom which may be cured upon the next transfer. Should, however, the breakage of the weft continue consecutively for a number of picks, it indicates some improper functional operation of the loom itself or of the shuttle, so that on such recurrence of weft breakage the loom must be stopped to investigate the cause of the defect.

In accordance with one aspect of the present invention, therefore, means are provided to effect loom stoppage on the first occurrence of a warp fault and to effect loom stoppage on repeated occurrences of a weft fault, usually three of such weft faults. A further feature of the present invention consists of a simplification of the mechanisms which effect loom stoppage and to utilize the weft fork mechanism to stop the loom either on the occurrence of a warp or a weft fault.

The invention and new combination of parts will best be made clear from the following description and the accompanying drawings of one good form thereof.

In the drawings:

Fig. 1 is a side elevation of a loom containing the present invention, some of the parts being shown in section;

Fig. 2 is an enlarged detached detail showing the weft fork stopping mechanism and the warp fault stopping mechanism in their associated relation;

Fig. 3 is a front elevation of details of mechanism for controlling the warp stop finger;

Fig. 4 is a longitudinal section through the weft fork stopping mechanism; and

Fig. 5 is a side elevation thereof with the knock-off lever shown in section.

The loom frame 1 may be of usual construction and be provided with the usual crank shaft 2 having the crank arm 3 connected to the pitman 4 which is itself connected to the lay 5 to impart thereto the usual beat-up movements.

Extending from the breast beam 6 is the shipper stand 7 having the shipper holding notch 8 which normally acts to retain the shipper 9 in running position, and the shipper, as indicated in Fig. 1, may be pivotally mounted on the bracket 10 at 11, as usual, the construction being such that when the shipper is in the holding notch, the loom will continue to run, but when detached from the holding notch, the shipper will be moved to a stopping position to throw the power from the loom.

Pivotally mounted at 12 upon the shipper stand is the shipper knock-off 13, the end portion 14 of which normally rests against the side of the shipper, and associated with the shipper knock-off are the warp control stop mechanism and the weft control stop mechanism.

The weft stop mechanism comprises the stand 15 in which the weft fork slide 16 is mounted for movement towards and from the front of the loom. Pivotally mounted on the weft fork slide 16 at 17 is the weft fork 18, the forwardly extending tail portion 19 of which is adapted to be engaged by a hook 20 carried by the weft hammer or cam follower 21, the construction being such that should the weft fork be tilted by engagement with a weft thread as the lay beats up, the hook 20 will not operatively engage the tail 19 of the weft fork and the loom will continue to run, but should the weft fork fail to be tilted owing to the absence of weft, the hook will engage the tail of the weft fork and

move the weft fork and weft fork slide forwardly. The mechanism so far described is of usual character and well understood.

Mounted loosely upon the weft fork slide is 5 the controller 22, having a laterally extending lug 23 and a transversely extending portion 24 which is adapted to rest at times in depressions 25 formed in the weft fork slide.

The parts, as indicated in Figs. 2 and 4, 10 with respect to the weft fork mechanism, are shown in their normal loom operating position, with the controller 22 having the transverse portion 24 resting in the front notch 25 of the slide. The rear portion of the controller 22 has a lug 26 extending upwardly 15 behind a bridge 27 carried by the weft fork slide, and below the lug 26 is a second lug 28 which is adapted to engage a projection 29 extending upwardly from the stationary 20 weft fork stand 15 when the weft fork slide is moved forwardly by the weft hammer on failure of weft, whereby the controller 22 is arrested in its forward movement with the weft fork slide, thereby positioning the 25 transverse projection 24 into the middle notch 25.

The controller 22 has a second shoulder 30 which, should a weft failure occur on the second beat-up movement of the lay, will engage 30 the stationary lug 29 and stop forward movement of the controller with the weft fork slide, thereby carrying the transverse projection 24 into the rear notch 25 of the weft fork slide. It will be noted that the rear 35 notch 25 in the weft fork slide is deeper than the other notches in order that the laterally extending projection 23 may be lowered into position to act upon the knock-off lever 13 when on a third failure of weft the weft fork 40 slide is moved forwardly. Under such conditions the lug 31 on the controller 22 engages the front portion of the bridge 27, with the result that the controller 22 is moved forwardly with the weft fork slide on the third 45 absence of filling, and the lug 23 will engage the end portion 34 of the knock-off lever 13 and detach the shipper from its holding notch to effect loom stoppage. The controller 22 has a lug 35 which normally rests upon a 50 lug 36 on the weft fork slide when the parts are in normal position, but when the controller is arrested on its first forward movement, the lug 35 drops from the lug 36 to enable the shoulder 30 of the controller to meet the projection 29 on the weft fork stand. It 55 will be understood, of course, that the weft fork slide is normally under the influence of a spring tending to hold it in its rearward position, and, in the present instance, this 60 spring is shown at 37, one end being secured to a pin 38 on the weft fork stand, and the other end secured at 39 to the front of the weft fork slide.

From the construction thus far described 65 it will be apparent that upon the first failure

of weft, the weft fork slide will be moved forwardly by the weft hammer or cam follower and the controller 22 will be arrested in its forward movement with the weft fork slide to cause the transverse projection 24 to 70 engage the center or the middle notch 25 in the weft fork slide. On the second failure of weft, the controller 22 will be arrested in its forward movement with the weft fork slide by engagement of its shoulder 30 with 75 the projection 29 and will thus cause the transverse projection 24 to drop into the deeper notch 25 and position the projection 23 for engagement with the end 34 of the knock-off on the third failure of weft as the weft fork 80 slide is moved forwardly and as indicated in Fig. 5. Thus loom stoppage on a weft fault will occur only after repeated failures of weft, a condition which is particularly advantageous in filling replenishing looms. 85

The warp stop mechanism is of the transversely movable toothed bar type, as generally indicated in Fig. 1. In the present illustration of the invention, there are four transversely movable toothed detector bars 40 90 each of which is connected to an actuator 41 mounted for rocking movement upon the shaft 42 and normally held for such rocking movement by yielding means, in which respect the construction is and may be substantially the same as that shown and described in the Harry A. Davis and Arthur S. Johnson Patent, No. 1,538,625, dated May 19, 1925, to which reference may be had for elucidation of the details of the warp stop mechanism. Secured to the rock shaft 42 is an arm 43 100 which receives its motion from a reach rod 44 which may be actuated from the lower or cam shaft. Extending upwardly beneath the cross member 45 of the warp stop mechanism is a plunger 46 which as more fully described in the Davis and Johnson patent, acts upon a sheathed wire transmitter 47 to move the wire longitudinally in its sheath when one of the transversely movable toothed bar detectors 105 is arrested in its transverse movement.

Mounted upon the knock-off 13 is a bracket 48 which may be secured to the knock-off by a bolt 49. The bracket 48 extends upwardly 110 from the knock-off and is provided with a laterally extending arm 50 to which is pivotally mounted at 51 the warp stop finger 52 which extends rearwardly from the arm 50 of the bracket between the side portions of the weft fork slide, and normally held in its raised position under the influence of means controlled from the warp stop mechanism, as will now be described.

Pivotedly mounted on the bracket 48 at 53 is the lever 54, the horizontal arm 55 of which 115 extends beneath the warp stop finger 52. The upwardly extending arm of the lever is under the influence of a spring 56, one end of which is secured by a pin 57 carried by the bracket 48, and the other end of which is 120

connected to the upwardly extending arm of the lever 54, as at 58. The tension of the spring 56 is such that under normal weaving conditions the lever 54 will be held with its 5 arm 55 pressed upwardly against the under side of the warp stop finger 52 to thereby maintain the finger 52 in its upper or inoperative position.

The horizontal arm 55 of the lever 54 is 10 provided with an abutment 59, Fig. 3, against which bears a plunger 60, the outer end portion of which rests against the sheathed wire 47, which, as hereinbefore noted, will be moved longitudinally in its sheath on the first 15 occurrence of a warp fault to thereby lower the arm 55 and permit the warp stop finger 52 to drop into position to be engaged by the hook or shoulder 20 of the weft hammer or cam follower 21, the construction being such 20 that upon the first occurrence of a warp fault, the finger 52, which is controlled from the warp stop mechanism, will be positioned to engage the same hook or shoulder of the cam follower which actuates the weft fork slide on 25 the absence of weft, so that on forward movement of the cam follower or weft hammer, the warp stop finger 52 will cause the knock-off 13 to be actuated to detach the shipper from its holding notch and effect loom 30 stoppage.

In the simplification of the weft fork stop mechanism and the warp stop mechanism it will be noted that the warp stop finger 52 moves to its operative engagement with the 35 weft fork mechanism or cam follower in a vertical plane passing through the weft fork or cam follower and between the side portions of the weft fork slide, thereby utilizing the weft fork mechanism to actuate the warp stop 40 control mechanism to effect loom stoppage.

From the construction hereinbefore described it will be apparent that upon the first occurrence of a warp fault the loom will be stopped through the action of the weft fork 45 mechanism or cam follower, and that upon occurrence of repeated weft faults the loom stopping mechanism will be actuated to stop the loom.

It may be desirable at times to limit the 50 upward movement of the horizontal arm 55 of the lever 54 under the action of the spring 56, and to this end the arm 50 of the bracket 48 is provided with a rearwardly extending stop 61, Fig. 2. This is desirable because on the 55 action of the warp stop mechanism, a slight movement downward of the horizontal arm 55 will cause the end of the warp stop finger 52 to engage the weft fork stop mechanism and effect loom stoppage.

60 What is claimed is:

1. In a loom, the combination of loom stopping mechanism including a shipper and shipper knock-off, a weft fork stopping mechanism including a weft fork slide, a cam 65 follower for operating the weft fork slide

of the stopping mechanism, a controller actuated by the weft fork stopping mechanism to stop the loom only on repeated absence of weft, a warp stop mechanism having a transversely movable toothed detector bar, and 70 means mounted on the shipper knock-off in position to extend over said slide and controlled by the transversely movable detector bar to engage the cam follower to effect loom stoppage on the first occurrence of a warp 75 fault without disturbing the position of said slide.

2. In a loom, the combination of loom stopping mechanism including a shipper and shipper knock-off, a weft fork stopping mechanism including a weft fork and weft fork slide, a controller mounted on the weft fork slide and actuated to stop the loom on the third absence of weft, a cam follower to act 80 upon the weft fork, a finger mounted on the shipper knock-off to extend over said slide and backwardly in the vertical plane passing through the weft fork, a warp stop mechanism comprising a transversely movable toothed detector bar adapted to be arrested 85 in its transverse movement on the occurrence of a warp fault, and means actuated by stoppage of the transverse movement of the detector bar to position the finger for engagement by the cam follower to stop the loom 90 on the first occurrence of a warp fault.

3. In a loom, weft fork stopping mechanism including a weft fork and weft fork slide, a cam follower adapted to engage the weft fork and move it and the slide forwardly on failure of weft to effect loom stoppage, loom stopping mechanism including a shipper and shipper knock-off, a warp stop finger mounted on the shipper knock-off and extending rearwardly in a vertical plane 100 between the sides of the weft fork slide in position for engagement with the cam follower, a warp stop mechanism having a transversely movable toothed detector bar, means normally holding the warp stop finger out of 105 the path of movement of the cam follower and positioned on the occurrence of a warp fault to cause the finger to engage the cam follower and stop the loom.

4. In a loom, the combination of loom stopping mechanism including a shipper and shipper knock-off, weft fork stopping mechanism including a weft fork slide, a cam follower to engage the weft fork to shift said slide, a warp stop finger mounted on the 115 shipper knock-off to extend over said slide in the vertical plane passing through the weft fork and cam follower, a warp stop mechanism, means controlled by the warp stop mechanism for placing the warp stop finger in position for engagement by the cam follower on the occurrence of a warp fault and operable to stop the loom without shifting said slide.

5. In a loom, the combination of loom 130

stopping mechanism including a shipper and shipper knock-off lever, weft fork stopping mechanism including a hollow weft slide having a weft fork and cam follower the upper 5 end of which reciprocates within the hollow slide, a warp stop finger mounted on the shipper knock-off in position to extend over said slide, means for normally holding said finger from engagement by the cam follower, 10 a warp stop mechanism having a movable detector bar, and means under the control of the warp stop mechanism for lowering said finger into engagement with the cam follower upon the occurrence of a warp fault and operable to stop the loom without shifting said 15 slide.

6. In a loom, the combination of loom stopping mechanism including a shipper and shipper knock-off lever, weft fork stopping

mechanism including a hollow weft slide having a weft fork and a cam follower the upper end of which reciprocates in the hollow slide and has a notch adapted to be engaged by the weft fork, a warp stop finger mounted on the shipper knock-off adjacent said slide, 20 means for normally holding said finger from engagement by the cam follower, a warp stop mechanism having a movable detector bar, and means under the control of the warp stop mechanism for effecting the engagement of 25 said finger with the notch of the cam follower upon the occurrence of a warp fault and operable to stop the loom without shifting said slide.

In testimony whereof, I have signed my 30 name to this specification.

HARRY A. DAVIS.
